Application March 16, 1954, Serial No. 29,564

Term of patent 14 years

(Cl. D93—3)

To all whom it may concern:

Be it known that we, Dorr D. Beale, John N. Polivka and George T. Scharfenberg, all citizens of the United States, residing at Minneapolis, county of Hennepin, Minneapolis, county of Hennepin, and Glen Lake, county of Hennepin, respectively, all in the State of Minnesota, have invented a new, original, and ornamental Design for a Jig Saw, of which the following is a specification, reference being had to the accompanying drawing, forming a part thereof:

Fig. 1 is a top plan view of a jig saw showing our new design;

Fig. 2 is a side elevational view thereof, the other side thereof being identically symmetrical with the side shown;

Fig. 3 is a front end elevational view thereof; Fig. 4 is a rear end elevational view thereof;

Fig. 5 is a vertical sectional view thereof taken substantially along the line 5—5 of Fig. 2; and

Fig. 6 is a vertical sectional view thereof taken substantially along the line 6—6 of Fig. 2.

We claim:

The ornamental design for a jig saw, substantially as shown and described.
